DESIGN FOR A COIN CONTROLLED PHONOGRAPH

Bayard E. Richardson and Richard W. Willey,
Grand Rapids, Mich.

Application July 13, 1935, Serial No. 57,621

Term of patent 3½ years

To all whom it may concern:

Be it known that we, Bayard E. Richardson and Richard W. Willey, citizens of the United States, residing at the city of Grand Rapids, in the county of Kent and State of Michigan, have invented a new, original, and ornamental Design for a Coin Controlled Phonograph, of which the following is a specification, reference being had to the accompanying drawing, forming a part thereof.

The figure is a perspective view of a coin controlled phonograph showing our new design, the side not shown being identical with the side shown.

We claim:

The ornamental design for a coin controlled phonograph as shown and described.

BAYARD E. RICHARDSON.
RICHARD W. WILLEY.
